UNITED STATES PATENT OFFICE.

FRANK REDMOND BLAKE, OF BANGOR, MAINE.

HANGER.

Application filed December 6, 1921. Serial No. 520,332.

To all whom it may concern:

Be it known that I, FRANK R. BLAKE, a citizen of the United States, residing at Bangor, in the county of Penobscot and State of Maine, have invented new and useful Improvements in Hangers, of which the following is a specification.

The present invention has reference to electric fixtures, and is particularly directed to a holding or supporting means therefor.

The primary object is the production of a simple, cheap and thoroughly effective means whereby an electric fixture can be hung and supported either from a ceiling or side wall of a building.

A further object is to produce a hanger for electric fixtures which includes a hook member designed to be passed between and engaged with a lath in a building construction, said hook having adjustable thereon a headless bolt, both the bolt and projecting portion of the hook being received in the fixture, and the outer end of the bolt being engaged by a nut which also engages the outer end of the fixture whereby to effectively support the fixture.

A further object is to produce a hanger for electric fixtures having means for engaging with the lath, studding or other portion of the building construction, an element adjustably associated with said first mentioned means, both the element and means being wholly received and fully covered by the fixture; and the said element having the end thereof engaged by a nut which likewise engages the outer end of the fixture to exert a binding action thereagainst and force the opposite end of the fixture against the wall or ceiling of a room.

The foregoing, and other objects which will appear as the nature of the invention is better understood, may be accomplished by a construction, combination and operative association of parts, such as is disclosed by the drawings which accompany and which form part of this specification.

In the drawings:—

Figure 1 is a view illustrating the application of the improvement, parts being broken away and parts being in section.

Figure 2 is a perspective view of the hanger with the elements constituting the same associated.

Figure 3 is a side elevation illustrating a modification.

In Figure 1 of the drawings, the hook of

the improvement is shown passed between two laths and engaging one lath in a wall of a building construction for supporting a side light electric fixture thereon, but, it is to be understood that the improvement may be employed with equal efficiency in supporting a fixture from a ceiling and that the hook, instead of engaging with the lath may engage with a studding or any other portion of a building construction.

Referring now to the drawings in detail, the numeral 1 designates a part of a wall of a building, 2 the laths which are secured to the studdings for supporting the plaster in the usual manner.

Either before or after the plaster is applied, there may be passed between two of the laths the hook portion of the improvement, or the said hook may be arranged on a lath when the same is nailed to the studding or in other words, the hook may be applied either before or after the building is plastered. The hook is indicated by the numeral 3, the same being constructed of a flat piece of metal, whereby the same will lie snugly against the inner face of the lath 2, and the beak 4 may contact with one of the edges of the lath. The end of the lath engaging portion of the hook opposite that provided with the beak has an angle extension 5 which terminates in what I will term an ear 6, the said ear being parallel with the lath engaging portion of the hook, and the ear is provided with a threaded opening. Screwed in the threaded opening is a headless bolt 7. When the parts are arranged as above described, the hollow electric fixture 8 is positioned thereover. The bolt 7 is adjusted so that the outer end thereof is arranged in a line with the outer end of the fixture 8, and the said outer end has screwed thereon a nut 9. This nut 9 may be of an ornamental nature. The nut 9 is designed to exert a frictional engagement against the outer end of the fixture forcing the bell end thereof against the wall. The bolt 7 is comparatively long, and therefore the hanger may be employed for effectively supporting fixtures of slightly different lengths.

In Figure 3, the hook element of the device is broadly indicated by the numeral 10, the hook having an inwardly directed beak 11. The body 12 of the hook has an angle portion which terminates in a straight end 13 that is parallel to the straight portion of the hook proper. The end 13 has a threaded

opening therethrough, and screwed through this opening is the headless bolt 14. The bolt has its inner end, that is the end next to the hook 10 provided with a head 15, the said head having its outer face provided with a hub 16, and the hub may be provided with a threaded bore which aligns with a similar bore in the head. In this threaded portion of the head the bolt 14 is 10 screwed. To hold the head on the bolt a binding element 17 may be employed, and when the head 15 is adjusted properly with respect to the hook a similar binding element 18 may enter the straight end 13 of the body 15 portion of the hook and contact with the screw 14.

The fixture is arranged over the screw and the body of the hook in a manner as heretofore described, the outer end of the screw 20 being engaged by a nut which also contacts with the fixture.

It is thought that the foregoing description, when taken in connection with the

drawings will fully set forth the construction, operation and advantages of the improvement to those skilled in the art to which such inventions relate, but it is to be understood that such changes may be made therefrom as fall within the scope of what is claimed. 25

Having described the invention, I claim:—

A means for supporting a fixture from a lathed and plastered wall, comprising a hook adapted to be inserted through the wall to engage with a lath of the wall structure, 35 said hook having its outer end formed with an angle ear having a threaded opening therethrough, a headless bolt threaded through said opening; an element thereon for contacting the wall, said bolt designed to pass through a fixture which surrounds the hook, and a nut screwed on the bolt for contacting the fixture to force the same against the wall. 40

In testimony whereof I affix my signature.
FRANK REDMOND BLAKE.
